TANK HEATER CONTROL SYSTEM

Clark M. Osterheld, Stoughton, Wis., assignor to
McGraw Electric Company, Elgin, Ill., a corpora-
tion of Delaware

Application July 17, 1944, Serial No. 545,351

12 Claims. (Cl. 219—39)

My invention relates to electric heating and particularly to control systems for electric heaters of domestic hot water storage tanks.

Among the objects of my invention are the following: to provide a control system that shall cause energization of the electric heater of a domestic hot water tank at any time during a twenty-four hour day when the tank is less than half full of hot water, such energization continuing until all of the water in the tank is hot, and that shall cause energization of the heater after a predetermined time delay period after closing of a time-controlled switch, such energization continuing until all of the water in the tank is hot.

Other objects of my invention will either be apparent from a description of several control systems embodying my invention or will be pointed out in the course of such description and set forth particularly in the appended claims.

In the drawings,

Figure 1 is a vertical, sectional view through a domestic hot water tank, with which is associated a control system embodying my invention,

Fig. 2 is a diagram of connections embodying my improved system of control,

Fig. 3 is a view similar to Fig. 1, and,

Fig. 4 is a diagram of connections of a modified form of control system embodying my invention.

Referring first of all to Fig. 1 of the drawings, I have there illustrated a domestic hot water tank 11 which is provided with a lower cold water inlet pipe 13, an upper hot water outlet pipe 15, a layer 17 of heat-insulating material, and an outer casing 19. All of these details are old and well known in the art and constitute no part of my present invention.

I provide a single electric heater 21, which is preferably located near to the bottom end of the tank and is preferably, although not necessarily, of a clamp-on type, which extends around the outside of the tank 11 and is positioned in a tunnel member 23.

My control system includes a lower thermally-actuable heater control switch, designated generally by the numeral 25 and including a tubular member 27, having a closed inner end and having its open outer end portion secured in a fluid-tight manner in an opening in tank 11, preferably a small distance above the heater 21. An expansion rod 29 is operatively positioned within the tube 27 and is adapted to engage with and be disengaged from a lug 31 of electric-insulating material secured to the free or movable end of

a resilient contact arm 33, which contact arm has a contact member thereon adapted to be engaged with and disengaged from a cooperating contact member on a substantially rigid contact arm 35. 5 The two contact arms 33 and 35 are suitably supported on blocks 37 of electric-insulating material. While I have shown a particular design of thermally-actuable switch, I do not desire to be limited thereto, but may use any other similar thermally-actuable switch known in the art. The cold water enters the tank 11 through the lower pipe 13, as hot water is withdrawn from the tank through the upper pipe 15, and the design construction, and adjustment of the thermally-actuable switch 25 is such that the two switch arms 33 and 35 will be in contacting engagement with each other when switch 25 is subject to cold water in the tank and will be disengaged from each other when switch 25, and particularly the tube 27, is subject to hot water in the tank. When I speak of cold water, I refer to water the temperature of which is on the order of 60 to 70° F., and when I speak of hot water, I refer to water the temperature of which has been raised to a value 10 on the order of say 150° F., although this may be raised or lowered slightly.

I provide a thermal retarder heater control switch unit 39, which is preferably located in heat-receiving relation on the tank 11 at substantially 15 the mid-height of the tank. For details of this thermal retarder heater control unit, reference may be had to my co-pending application, S. N. 537,941, filed May 29, 1944, and assigned to the same assignee as is the present application. While 20 the above identified application shows only two switches, the design and construction of the switches shown in the present application is similar thereto.

The thermal retarder unit includes a first thermal switch, comprising a bimetal bar 41, having one end thereof fixed, and having a forked other end with pivot plates 43 fixed on the side portions, which pivot plates are adapted to be engaged by the two spaced pointed inner ends of a second bimetal bar 45, having a forked inner end portion, the two bimetal bars being severally provided with longitudinally-extending slots at their adjacent ends, in which slots is located an over center spring 47, the ends of which are connected to the bimetal bars 41 and 45 just beyond the ends of the central longitudinal slots to cause movement of the outer end of bimetal bar 45 with a snap action. The outer end of bimetal bar 45 has insulated and loosely mounted thereon a contact bridging member 49 adapted to engage with

and be disengaged from two fixed contacts 51 and 53. The design, construction, and adjustment of the first thermal heater control switch of the thermal retarder unit is such that the switch will be in closed position, that is contact bridging member 49 will be in engagement with the contacts 51 and 53, when the thermal retarder is subject to cold water in the tank, that is when enough hot water has been withdrawn from the tank to subject not only the lower thermally-actuable switch 25 to cold water, but also the thermal retarder switch unit 39, which may be located at the mid-height of the tank or above or below such fixed position. A stop member 55 is provided, which is adapted to be engaged by the free end of the outer bimetal bar 45 when the thermal retarder switch unit is subject to hot water in the tank.

I provide further a second thermal switch, comprising a part of the thermal retarder switch unit and including a first bimetal bar 57 having one end thereof mounted in fixed position and having its forked other end provided with pivot plates 43, which pivot plates are adapted to be engaged by the pointed ends of a second bimetal bar 59 having a forked inner end. An over center spring 61 is positioned within longitudinally-extending slots in the adjacent end portions of bimetal bars 57 and 59 so that movement of the free end of the bimetal bar 59 will be effected with a snap action. The outer end of bimetal bar 59 has loosely insulatedly mounted thereon a contact bridging member 63 adapted to engage with and be disengaged from a pair of fixed contacts 65 and 67. The design, construction, and adjustment of the second thermal switch, comprising particularly the bimetal bars 57 and 59, are such that the contact bridging member 63 will be out of engagement with the contact members 65 and 67 when the thermal retarder switch is subject to cold water in the tank and to hot water in the tank, and will be in engagement with the fixed contact members 65 and 67 at an appreciably higher temperature, which may be on the order of 250° F. When the second thermal switch is in its open position, the outer end of the second bimetal bar 59 engages a stop member 69.

Means for raising the temperature of the bimetal bars 57 and 59 include a heating coil 71, which is insulatedly mounted on and wrapped around the bimetal bar 57 and carries a relatively small current, so that it will require from four to six hours before the temperature of particularly the bimetal bar 57 will be raised to a value on the order of 250° F., with resultant snap-acting movement of bimetal bar 59 to its other operative closed position.

I provide further an electromagnetic switch designated by numeral 73, said switch comprising a pair of fixed contact members 75 and 77, a contact bridging member 79, which is insulatedly connected with and movable by an electromagnetic armature core 81, which armature core is adapted to be energized by a coil 83. Electromagnetic switches of this kind are old and well known in the art.

I provide further a time-controlled switch designated generally by the numeral 85, and while I have shown two contact or switch arms 87 and 89 only, I desire it to be clearly understood that I provide in addition thereto, any time-telling device, which may be a mechanical clock or which may be an electric motor operative continuously to cause closure of the switch 85 at off-peak periods during a twenty-four day. The energiza-

tion of heating coil 71 is controlled jointly by the lower thermal switch 25 and the time-controlled switch 85.

I provide a pair of supply circuit conductors 91 and 93, contact arm 87 being connected to supply circuit conductor 91. I provide a conductor 95 connecting arm 87 to contact terminal 75, while contact terminal 77 is connected by a conductor 97 with a conductor 99, connecting one terminal of heater 21 to the two terminals 51 and 65 of the two thermal switches of the thermal retarder unit. The second contact 53 of the first thermal switch is connected by a conductor 101 to contact arm 87 and to the first supply circuit conductor 91. A conductor 103 connects contact arm 89 of the time-controlled switch with contact 67 of the second thermal switch, which contact 67 is connected by a conductor 105 with one terminal of heating coil 71, the other terminal of which is connected by a conductor 107 with the rigid contact arm 35 of the lower thermally-actuable switch 25. The other terminal of heater 21 is connected by conductor 109 with contact arm 35. A conductor 111 connects contact arm 33 with one terminal of coil 83, the other terminal of which is connected by a conductor 113 with the second supply circuit conductor 93.

The general object of my invention is to provide a control system that shall be effective to ensure that in case only a relatively small quantity of hot water has been withdrawn from the tank during a twenty-four hour day, energization of the heater will be delayed until after a predetermined time delay period after closing of the time clock; but that if a relatively large quantity of hot water is withdrawn from the tank, energization of the heater will be effected as soon as the thermal retarder unit is subject to cold water, irrespective of the position of the time-controlled switch, said energization continuing until substantially all of the water in the tank is hot.

Let it be assumed that only a relatively small quantity of cold water is in the tank during an on-peak period, sufficient to subject tube 27 to cold water, but not enough to subject the thermal retarder unit 39 to cold water. Under these conditions the switch arms 33 and 35 will be in engaged position; the first thermal switch, including bimetal bar 41, will be in open position; the time-controlled switch 85 will also be in open position; and the second thermal switch of the thermal retarder unit will also be in open position. Energization of the heating coil 71 will be effected upon closure of the time-controlled switch 85 through a circuit substantially as follows: from the supply circuit conductor 91, through closed switch 85, through conductors 103 and 105, heating coil 71, conductor 107, through closed switch 25, conductor 111, coil 83, and through conductor 113 to the second supply circuit conductor 93. This will cause temperature rise of the second thermal switch, which will reach its predetermined maximum value on the order of 250° F., with resultant snap-acting movement of the contact bridging member 63 into position to engage contact terminals 65 and 67, after a time delay period on the order of four to six hours. When closure of the second thermal switch occurs, the following energizing circuit through heater 21 is effected: from the first supply circuit conductor 91, through closed switch 85, conductor 103, through closed second thermal switch of the thermal retarder unit comprising contacts 67, 65, and contact bridging member 63, then through conductor 99, heater 21, conductor

109, closed switch 25, through conductor 111, coil 83, and through conductor 113 to the second supply circuit conductor 93. The energized coil 83 causes upward movement of the core 81 and attendant engagement of the contacts 75 and 77 by contact bridging member 79, thereby closing another energizing circuit through heater 21, which is independent of the time-controlled switch 85. This circuit is as follows: from the first supply circuit conductor 91, through conductor 95, through the engaged contact members 75 and 77 and contact bridging member 79, through conductors 97 and 99, heater 21, conductor 109, closed switch 25, conductor 111, coil 83, and conductor 113 to the second supply circuit conductor 93. Irrespective now of whether the time-controlled switch 85 is closed or is open, energization of the heater 21 will continue until substantially all of the water in the tank is hot, when opening of the lower thermally-actuable switch 25 will occur with attendant deenergization of heater 21. This operation may be caused by extraordinary demands for hot water during late night hours before all of the cold water in the lower part of the tank has been heated to a predetermined high temperature.

Let it now be assumed that sufficient hot water was withdrawn from the tank to subject not only the lower thermally-actuable switch 25 to cold water, but also the thermal retarder unit 39. This will cause immediate reclosure of the first thermal switch, comprising bimetal bars 41 and 45, to the position shown in full lines in Fig. 2, resulting in closing an energizing circuit for heater 21 traceable as follows: from first supply circuit conductor 91 through conductor 101, through the engaged contact members 53 and 51 with contact bridging member 49, through conductor 99, heater 21, conductor 109, closed switch 25, conductor 111, coil 83, and conductor 113, to the second supply circuit conductor 93. The energized coil 83 will cause upward movement of armature core 81 and of contact bridging member 79, with the result that the hereinbefore described energizing circuit, through heater 21 and through the electromagnetic switch contacts and contact bridging member, will be effected, which will permit of continuing energization of the heater 21, irrespective of the position of the time-controlled switch, until substantially all the water in the tank is hot, when tube 27 will be subject to hot water with resultant disengagement of contact arms 33 and 35 and attendant deenergization of the heater 21 and of the coil 83 of the electromagnetic switch.

Referring now to Figs. 3 and 4 of the drawings, I have there shown a similar domestic hot water tank, as shown in Fig. 1, having mounted thereon a lower thermally-actuable heater control switch 25, but having a different form of thermal retarder switch 114 mounted in heat-receiving relation to the tank at substantially the mid-height thereof.

This thermal retarder heater control unit includes a first thermal switch, substantially the same as hereinbefore described in connection with Fig. 2 of the drawings, as well as a second thermal switch comprising bimetal bars 57 and 59, the latter bimetal bar having insulatedly mounted thereon a contact bridging member 63. In order to simplify the explanation of the control embodying this form of thermal retarder, the elements of the first and of the second thermal switch have been given the same numerals as used in Fig. 2 of the drawings.

I provide a third thermal switch, constituting a part of the thermal retarder unit and including a first bimetal bar 115 having one end fixed and having pivot plates 117 thereon at its other forked end which are engaged by the pointed ends of a second bimetal bar 119, both of said bars having at their adjacent ends a slot therein, in which slot is positioned an over center spring 121, the ends of which are suitably secured to the bimetal bars 115 and 119 beyond the ends of the respective slots to cause snap-acting movement of the free end of bar 119 in response to temperature changes. A contact bridging member 123 is insulatedly mounted on the outer end of bimetal bar 119 and is adapted to engage with and be disengaged from a cooperating pair of fixed contact members 125 and 127 with a snap action. When contact bridging member 123 is out of engagement with the fixed contacts 125 and 127, bar 119 is adapted to be in operative engagement with a stop member 129. The bimetal bar 115 has insulatedly mounted thereon a heating coil 131 which is adapted to carry the same current as traverses the heater 21 and is adapted to raise the temperature of the bimetal bar 115 to a value on the order of 250° F. to cause the normally open switch to be moved with a snap action to closed position. It may be here repeated that the first thermal switch, including bimetal bars 41 and 45, is adapted to be in closed position when subject to cold water in the tank and to be in open position when subject to hot water in the tank, and that the second thermal switch, including bars 57 and 59, is adapted to be in open position when subject to cold and to hot water in the tank, but to be moved with a snap action to closed position when subject to a temperature on the order of 250° F.

The first supply circuit conductor 91 is connected to the first resilient contact arm 87 of the time-controlled switch and is connected by conductor 101 with terminal 53 of the first thermal switch, which terminal is connected by a conductor 133 to the terminal 127 of the third thermal switch of the thermal retarder unit. The two contacts 51 and 125 of the first and third thermal switches are connected by a conductor 135, which conductor is connected by a conductor 137 to one terminal of heating coil 131, the other terminal of which is connected by a conductor 139 to one terminal of heater 21, the other terminal of which is connected by a conductor 109 with substantially rigid contact arm 35. The other contact arm 33 of the lower thermally-actuable switch 25 is connected by a conductor 141 with the second supply circuit conductor 93. The second contact arm 89 of the time-controlled switch is connected by conductor 103 with contact 67 of the second thermal switch, which contact is connected by a conductor 105 with one terminal of heating coil 71 on bimetal bar 57, the other terminal of which is connected by a conductor 107 with the rigid contact arm 35 of the lower thermally-actuable switch 25. The first terminal of heating coil 131 of the third thermal switch of the thermal retarder unit and conductor 137 are connected by a conductor 143 with contact 65 of the second thermal switch of the thermal retarder unit.

Let it now be assumed that sufficient hot water has been withdrawn from the tank to subject not only the lower thermally-actuable switch 25 to cold water, but also to subject the thermal retarder switch unit to cold water, with the result that the first thermal switch, comprising bimetal bars

41 and 45, has been moved with a snap action into the position shown in full lines in Fig. 4 of the drawings, that is contact bridging member 49 is in engagement with contacts 51 and 53. In this case, an energizing circuit will be closed through 5 heater 21, traceable as follows: from the first supply circuit conductor 91 through conductor 101, through the closed switch of the first thermal switch, comprising contact bridging member 49 and contacts 51 and 53, through conductor 137, 10 through heating coil 131, conductor 139, heater 21, conductor 109, through the closed switch 25, and through conductor 141 to the second supply circuit conductor 93. Energization of heater 21 through this circuit will continue for a relatively 15 short period of time, say on the order of fifteen to thirty minutes, that is until the energized coil 131 has caused an increase in the temperature of bimetal bar 115 to a value on the order of say 250° F., when snap-acting movement of contact bridging member 123 into engagement with contacts 125 and 127 will take place, causing a new 20 circuit to be closed through heater 21, traceable as follows: from supply circuit conductor 91, conductors 101 and 133, through the engaged contact members 125 and 127 with contact bridging member 123, through conductor 137, coil 131, conductor 139, heater 21, conductor 109, engaged contact arms 35 and 33, and through conductor 141 to the second supply circuit conductor 93. Within a relatively short time, which may be on 25 the order of one or two hours, depending upon the amount of cold water in the tank above the thermal retarder switch unit, and the raising of the temperature of this quantity of cold water to a value on the order of 150° F., with resultant opening movement of the first thermal switch of the thermal retarder switch unit, with attendant disengagement of contact bridging member 49 from 30 contacts 51 and 53 will be effected. When this happens, the energization of heater 21 will continue through the last above described circuit, which energization will continue until substantially all of the water in the tank is hot, irrespective of the position of the time-controlled switch 85, with attendant subjecting of the lower thermally-actuable heater control switch 25 to hot water and opening movement of the switch controlled by the expansion 35 rod 29 and attendant deenergization of heater 21 when substantially all of the water in the tank is hot. It will be noted that the operation of the third thermal retarder switch hereinbefore described is substantially the same as that of the electromagnetic switch shown in Fig. 2 of the 40 drawings.

Let it now be assumed that only a relatively small quantity of hot water has been withdrawn from the tank, the quantity being such as to cause entrance of cold water into the tank only sufficient to subject the lower thermally-actuable switch 25 to cold water. When this happens at any time during on-peak hours, that is with the time-controlled switch 85 in open position, no energization of heater 21 can be effected, but as soon as closure of the time-controlled switch 85 occurs, an energizing circuit will be closed through heating coil 71 of the second thermal switch comprising the bimetal bars 57 and 59, this circuit being traceable as follows: from the first supply circuit conductor 91, through contact arms 87 and 89 which are now engaged, through conductors 103 and 105, heating coil 71, conductor 107, through closed switch 25, and through conductor 141 to the second supply circuit conductor

53. After a time period of delay on the order of four to six hours, the second thermal switch will have had its temperature raised to a value which will cause snap-acting movement of the contact bridging member 63 into engagement with contacts 65 and 67, whereby an energizing circuit through heater 21 is effected, traceable as follows: from the first supply circuit conductor 91, closed switch 85, conductor 103, engaged contact members 65 and 67 and contact bridging member 63, conductor 143, heating coil 131 of the third thermal switch, conductor 139, heater 21, conductor 109, closed switch 25, and through conductor 141 to the second supply circuit conductor 93. This energizing circuit will continue for a relatively short period of time until the heating coil 131 of the third thermal switch has raised the temperature thereof to a value sufficient to cause snap-acting movement of contact bridging member 123 into engagement with contacts 125 and 127, when a new energizing circuit through heater 21 is closed as follows: from the first supply circuit conductor 91, through conductors 101 and 133, through contacts 127 and 125 and contact bridging member 123, through conductors 135 and 137, heating coil 131, conductor 139, heater 21, conductor 109, closed switch 25, conductor 141, to the second supply circuit conductor 93. Energization of the heater 21 will therefore continue, irrespective of the position of the time-controlled switch 85, until substantially all of the water in the tank is hot, when opening of the lower thermally-actuable switch 25 will cause deenergization of the heater 21 with a full tank of water. Such operation will be effected in case of extraordinary demands for hot water during late night hours before all of the cold water in the lower part of the tank has been heated to a predetermined high temperature.

It may be here pointed out that the two forms of control systems shown in Figs. 2 and 4 of the drawings are such as to ensure that a full tank of hot water will be provided at the start of daylight hours, even though extraordinary demands for hot water are made upon the tank during the late night hours, as in case of sudden illness among the members of the family. In case relatively large withdrawals of hot water occur during the on-peak hours or periods of a twenty-four hour day, immediate energization of the heater will take place, which energization will continue until substantially all of the water in the tank is hot.

Various modifications may be made in the systems embodying my invention without departing from the spirit and scope thereof, and all such modifications coming clearly within the scope of the appended claims are to be considered as covered thereby.

I claim as my invention:

1. A control system for a hot water tank having an electric heater, comprising a lower thermally-actuable heater control switch located on 65 the tank adjacent the lower end thereof, a time-controlled switch adapted to be in open position during on-peak periods of the day, a thermal retarder heater control switch unit mounted on the tank intermediate the ends thereof and including a first thermal switch adapted to be in closed position when subject to cold water in the tank and to be in open position when subject to hot water in the tank, and a second thermal switch adapted to be in open position when subject to hot water in the tank and to be in

closed position when heated to an appreciably higher temperature, and a heating coil for said second thermal switch, a third switching means connected in shunt with said time switch and said second thermal switch, and other electric connections between said switches and said electric heater to cause immediate energization of said heater in case said thermal retarder unit is subject to cold water in the tank, irrespective of the position of the time-controlled switch.

2. A control system for a hot water tank having an electric heater, comprising a lower thermally-actuable heater control switch located on the tank adjacent the lower end thereof, a time-controlled switch adapted to be in open position during on-peak periods of the day, a thermal retarder heater control switch unit mounted on the tank intermediate the ends thereof and including a first thermal switch adapted to be in closed position when subject to cold water in the tank and to be in open position when subject to hot water in the tank, and a second thermal switch adapted to be in open position when subject to hot water in the tank and to be in closed position when heated to an appreciably higher temperature, and a heating coil for said second thermal switch, a third switching means connected in shunt with said time switch and said second thermal switch, and other electric connections between said switches and said electric heater to cause immediate energization of said heater in case said thermal retarder unit is subject to cold water in the tank, irrespective of the position of the time-controlled switch, and a second thermal switch adapted to be in open position when subject to hot water in the tank and to be in closed position when heated to an appreciably higher temperature, and a heating coil for said second thermal switch, a third switching means connected in shunt with said time switch and said second thermal switch, and other electric connections between said switches and said electric heater to cause immediate energization of said heater in case said thermal retarder unit is subject to cold water in the tank, irrespective of the position of the time-controlled switch, and to prevent energization of said heater for a predetermined length of time after closing of said time-controlled switch in case only the lower thermally-actuable switch is subject to cold water.

3. A control system for a hot water tank having an electric heater, comprising a lower thermally-actuable heater control switch located on the tank adjacent the lower end thereof, a time-controlled switch adapted to be in open position during on-peak periods of the day, a thermal retarder heater control switch unit mounted on the tank intermediate the ends thereof and including a first thermal switch adapted to be in closed position when subject to cold water in the tank and to be in open position when subject to hot water in the tank, and a second thermal switch adapted to be in open position when subject to hot water in the tank and to be in closed position when heated to an appreciably higher temperature, and a heating coil for said second thermal switch, a third switching means connected in shunt with said time switch and said second thermal switch, and other electric connections between said switches and said electric heater to cause immediate energization of said heater through said lower thermally-actuable switch and said first thermal switch of the thermal retarder unit and continuing through said third switching means and said lower thermally-actuable switch until substantially all of the water in the tank is hot.

4. A control system for a domestic hot water tank having an electric heater, subject to withdrawal of varying quantities of hot water during a twenty-four hour day, comprising a lower thermally-actuable heater control switch positioned in heat-receiving relation on the tank adjacent to the lower end thereof and adapted to be in closed position when subject to cold water in the tank and to be in open position when subject to hot water in the tank, a time-controlled switch adapted to be in closed position during off-

peak periods only, a thermal retarder heater control switch unit mounted in heat-receiving relation on the tank intermediate the ends thereof and including a first thermal switch adapted to be in closed position when subject to cold water in the tank and to be in open position when subject to hot water in the tank, a second thermal switch adapted to be in open position when subject to cold and to hot water in the tank and to be in closed position when heated to an appreciably higher temperature and a heating coil for said second thermal switch, the energization of which is controlled jointly by said time-controlled and said lower thermally-actuable switch, a normally-open third switching means connected in shunt with said time-controlled and said second thermal switch and adapted to be moved into closed position by the current traversing said heater and other connections between said switches and said heater to cause immediate energization of said heater in case said thermal retarder is subject to cold water in the tank, irrespective of the position of the time-controlled switch, and to prevent energization of said heater for a predetermined length of time after closing of said time-controlled switch in case only the lower thermally-actuable switch is subject to cold water.

5. A control system for a domestic hot water tank having an electric heater, subject to withdrawal of varying quantities of hot water during a twenty-four hour day, comprising a lower thermally-actuable heater control switch positioned in heat-receiving relation on the tank adjacent to the lower end thereof and adapted to be in closed position when subject to cold water in the tank and to be in open position when subject to hot water in the tank, a time-controlled switch adapted to be in closed position during off-peak periods only, a thermal retarder heater control switch unit mounted in heat-receiving relation on the tank intermediate the ends thereof and including a first thermal switch adapted to be in closed position when subject to cold water in the tank and to be in open position when subject to hot water in the tank, a second thermal switch adapted to be in open position when subject to cold and to hot water in the tank and to be in closed position when heated to an appreciably higher temperature and a heating coil for said second thermal switch, the energization of which is controlled jointly by said time-controlled and said lower thermally-actuable switch, a normally-open third switching means connected in shunt with said time-controlled and said second thermal switch and adapted to be moved into closed position by the current traversing said heater and other connections between said switches and said heater to cause immediate energization of said heater in case said thermal retarder is subject to cold water in the tank, irrespective of the position of the time-controlled switch and to cause energization of said heater after a predetermined time period of delay after closing of said time-controlled switch in case only the lower thermally-actuable switch is subject to cold water.

6. A control system for a domestic hot water tank having an electric heater, subject to withdrawal of varying quantities of hot water during a twenty-four hour day, comprising a lower thermally-actuable heater control switch positioned in heat-receiving relation on the tank adjacent to the lower end thereof and adapted to be in closed position when subject to cold water in the tank

and to be in open position when subject to hot water in the tank, a time-controlled switch adapted to be in closed position during off-peak periods only, a thermal retarder heater control switch unit mounted in heat-receiving relation on the tank intermediate the ends thereof and including a first thermal switch adapted to be in closed position when subject to cold water in the tank and to be in open position when subject to hot water in the tank, a second thermal switch adapted to be in open position when subject to cold and to hot water in the tank and to be in closed position when heated to an appreciably higher temperature and a heating coil for said second thermal switch, the energization of which is controlled jointly by said time-controlled and said lower thermally-actuable switch, a normally-open third switching means connected in shunt with said time-controlled and said second thermal switch and adapted to be moved into closed position by the current traversing said heater and other connections between said switches and said heater to cause immediate energization of said heater in case said thermal retarder is subject to cold water in the tank, irrespective of the position of the time-controlled switch and to cause energization of said heater after a predetermined time period of delay after closing of said time-controlled switch in case only the lower thermally-actuable switch is subject to cold water, deenergization of said heater being effected by said lower thermally-actuable switch when substantially all of the water in the tank is hot.

7. A control system for a hot water tank having an electric heater, comprising a lower thermally-actuable heater control switch located on the tank adjacent the lower end thereof, a time-controlled switch, a thermal retarder switch means mounted on the tank intermediate the ends thereof and including a first thermal switch adapted to be in closed position when subject to cold water and to be in open position when subject to hot water, a second thermal switch adapted to be in open position when subject to hot water and to be in closed position when heated to an appreciably higher temperature, and a heating coil for said second thermal switch, an electromagnetic switch connected in shunt circuit with said time-controlled switch and said second thermal switch and other electric connections between said switches and said heater to cause immediate energization of said heater in case of said thermal retarder switch means being subject to cold water in the tank, irrespective of the position of the time-controlled switch.

8. A control system for a hot water tank having an electric heater, comprising a lower thermally-actuable heater control switch located on the tank adjacent the lower end thereof, a time-controlled switch, a thermal retarder switch means mounted on the tank intermediate the ends thereof and including a first thermal switch adapted to be in closed position when subject to cold water and to be in open position when subject to hot water, a second thermal switch adapted to be in open position when subject to hot water and to be in closed position when heated to an appreciably higher temperature, and a heating coil for said second thermal switch, an electromagnetic switch connected in shunt circuit with said time-controlled switch and said second thermal switch and other electric connections between said switches and said heater to cause immediate energization of said heater in case of

said thermal retarder switch means being subject to cold water in the tank, irrespective of the position of the time-controlled switch, said lower thermally-actuable switch being effective to cause deenergization of the heater when substantially all of the water in the tank is hot.

9. A control system for a domestic hot water tank having an electric heater, subject to withdrawal of varying quantities of hot water during a twenty-four hour day, comprising a lower thermally-actuable heater control switch positioned in heat-receiving relation on the tank adjacent to the lower end thereof and adapted to be in closed position when subject to cold water in the tank and to be in open position when subject to hot water in the tank, a time-controlled switch adapted to be in closed position during off-peak periods only, a thermal retarder heater control switch unit mounted in heat-receiving relation on the tank intermediate the ends thereof and including a first thermal switch adapted to be in closed position when subject to cold water in the tank and to be in open position when subject to hot water in the tank, a second thermal switch adapted to be in open position when subject to cold and to hot water in the tank and to be in closed position when heated to an appreciably higher temperature and a heating coil for said second thermal switch, the energization of which is controlled jointly by said time-controlled and said lower thermally-actuable switch, a normally-open third switching means connected in shunt with said time-controlled and said second thermal switch and adapted to be moved into closed position by the current traversing said heater and other connections between said switches and said heater to cause immediate energization of said heater through said lower thermally-actuable switch and said first thermal switch in case said thermal retarder is subject to cold water in the tank, irrespective of the position of the time-controlled switch, and to continue energization of said heater through said lower thermally-actuable switch and said third switching means until substantially all of the water in the tank is hot.
10. A control system for a domestic hot water tank having an electric heater, subject to withdrawal of varying quantities of hot water during a twenty-four hour day, comprising a lower thermally-actuable heater control switch positioned in heat-receiving relation on the tank adjacent to the lower end thereof and adapted to be in closed position when subject to cold water in the tank and to be in open position when subject to hot water in the tank, a time-controlled switch adapted to be in closed position during off-peak periods only, a thermal retarder heater control switch unit mounted in heat-receiving relation on the tank intermediate the ends thereof and including a first thermal switch adapted to be in closed position when subject to cold water in the tank and to be in open position when subject to hot water in the tank, a second thermal switch adapted to be in open position when subject to cold and to hot water in the tank and to be in closed position when heated to an appreciably higher temperature and a heating coil for said second thermal switch, the energization of which is controlled jointly by said time-controlled and said lower thermally-actuable switch, a normally-open third switching means connected in shunt with said time-controlled and said second thermal switch and adapted to be moved into closed position by the current traversing said heater and other connections between said switches and said heater to cause immediate energization of said heater through said lower thermally-actuable switch and said first thermal switch in case said thermal retarder is subject to cold water in the tank, irrespective of the position of the time-controlled switch, and to continue energization of said heater through said lower thermally-actuable switch and said third switching means until substantially all of the water in the tank is hot.
11. A control system for a domestic hot water tank having an electric heater, subject to withdrawal of varying quantities of hot water during a twenty-four hour day, comprising a lower thermally-actuable heater control switch positioned in heat-receiving relation on the tank adjacent to the lower end thereof and adapted to be in closed position when subject to cold water in the tank and to be in open position when subject to hot water in the tank, a time-controlled switch adapted to be in closed position during off-peak periods only, a thermal retarder heater control switch unit mounted in heat-receiving relation on the tank intermediate the ends thereof and including a first thermal switch adapted to be in closed position when subject to cold water in the tank and to be in open position when subject to hot water in the tank, a second thermal switch adapted to be in open position when subject to cold and to hot water in the tank and to be in closed position when heated to an appreciably higher temperature and a heating coil for said second thermal switch, the energization of which is controlled jointly by said time-controlled and said lower thermally-actuable switch, a normally-open third switching means connected in shunt with said time-controlled and said second thermal switch and adapted to be moved into closed position by the current traversing said heater and other connections between said switches and said heater to cause immediate energization of said heater through said lower thermally-actuable switch and said first thermal switch in case said thermal retarder is subject to cold water in the tank, irrespective of the position of the time-controlled switch, and to continue energization of said heater through said lower thermally-actuable switch and said third switching means until substantially all of the water in the tank is hot.

heater to cause energization of said heater after a predetermined time period of delay after closure of said time-controlled switch through said lower thermally-actuable switch, said second thermal switch and said time-controlled switch in case only the lower thermally-actuable switch is subject to cold water at the time of closure of the time-controlled switch, said energization continuing through said lower thermally-actuable switch and said third switching means until substantially all of the water in the tank is hot, when deenergization of the heater is effected by said lower thermally-actuable switch.

11. A control system for a domestic hot water tank having an electric heater, subject to withdrawal of varying quantities of hot water during a twenty-four hour day, comprising a lower thermally-actuable heater control switch positioned in heat-receiving relation on the tank adjacent to the lower end thereof and adapted to be in closed position when subject to cold water in the tank and to be in open position when subject to hot water in the tank, a time-controlled switch adapted to be in closed position only during off-peak periods, a thermal retarder heater control switch unit mounted in heat-receiving relation on the tank intermediate the ends thereof and including a first bimetal snap-acting switch adapted to be in closed position when subject to cold water in the tank and to be in open position when subject to hot water in the tank, a second bimetal snap-acting switch adapted to be in open position when subject to cold and to hot water in the tank and to be in closed position when heated to an appreciably higher temperature, a heating coil for said second switch, the energization of which is controlled jointly by said lower thermally-actuable switch and said time-controlled switch, a third bimetal snap-acting switch adapted to be in open position when subject to cold and to hot water in the tank and to be in closed position when heated to a substantially higher temperature and connected in shunt circuit with said time-controlled and said second thermal switch, and a heating coil for said third switch energized by the heater current and other connections between said switches and said heater to cause immediate energization of said heater through said lower thermally-actuable switch and said first snap-acting switch in case said thermal retarder switch unit is subject to cold water and to continue said energization through said lower thermally-actuable switch and said third snap-acting switch until substantially all of the water in the tank is hot.

12. A control system for a domestic hot water tank having an electric heater, subject to withdrawal of varying quantities of hot water during a twenty-four hour day, comprising a lower thermally-actuable heater control switch positioned in heat-receiving relation on the tank adjacent to the lower end thereof and adapted to be in closed position when subject to cold water in the tank and to be in open position when subject to hot water in the tank, a time-controlled switch adapted to be in closed position only during off-peak periods, a thermal retarder heater control switch unit mounted in heat-receiving relation on the tank intermediate the ends thereof and including a first bimetal snap-acting switch adapted to be in closed position when subject to cold water in the tank and to be in open position when subject to hot water in the tank, a second bimetal snap-acting switch adapted to be in open position when subject to cold and to hot water in the tank and to be in closed position when heated to an appreciably higher temperature, a heating coil for said second switch, the energization of which is controlled jointly by said lower thermally-actuable switch and said time-controlled switch, a third bimetal snap-acting switch adapted to be in open position when subject to cold and to hot water in the tank and to be in closed position when heated to a substantially higher temperature and connected in shunt circuit with said time-controlled and said second thermal switch, and a heating coil for said third switch energized by the heater current and other connections between said switches and said heater to cause immediate energization of said heater through said lower thermally-actuable switch and said first snap-acting switch in case said thermal retarder switch unit is subject to cold water and to continue said energization through said lower thermally-actuable switch and said third snap-acting switch until substantially all of the water in the tank is hot, and to cause energization of said heater with a predetermined time delay after closure of the time-controlled switch, through said lower thermally-actuable switch, said second snap-acting switch and said time-controlled switch in case only said lower thermally-actuable switch is subject to cold water and to continue said energization through said lower thermally-actuable switch and said third snap-acting switch until substantially all of the water in the tank is hot when deenergization of the heater is effected by said lower thermally-actuable switch.

CLARK M. OSTERHELD.
